DISPLAY STAND FOR ART OBJECTS
OR THE LIKE

Joan P. Gardner, 2637 Buchanan St.,
San Francisco, Calif. 94115

Filed July 22, 1969, Ser. No. 18,282

Term of patent 14 years

Int. Cl. D6—01

U.S. Cl. D80—9

FIG. 1.

FIG. 2.

FIG. 3.

FIG. 4.

FIG. 2 is a top plan view thereof.

FIG. 3 is a front elevational view thereof.

FIG. 4 is a side elevational view thereof.

The broken line representation of sea shells in FIGS. 1, 3 and 4 is for purposes of illustration only.

I claim:

The ornamental design for a display stand for art objects or the like, substantially as shown and described.
